UNITED STATES PATENT OFFICE.

WILLIAM J. HINES, OF LEOMINSTER, MASSACHUSETTS, ASSIGNOR TO PURITAN COMB COMPANY, OF LEOMINSTER, MASSACHUSETTS, A CORPORATION OF MASSACHUSETTS.

HAIR ORNAMENT.

1,020,424.

Specification of Letters Patent. Patented Mar. 19, 1912.

Application filed November 12, 1910. Serial No. 591,993.

To all whom it may concern:

Be it known that I, WILLIAM J. HINES, a citizen of the United States, residing at Leominster, in the county of Worcester and 5 State of Massachusetts, have invented a new and useful Hair Ornament, of which the following is a specification.

This invention relates to a method of uniting metal with celluloid and to a new 10 and improved article of manufacture made by said method, said article of manufacture preferably consisting of a hair ornament having a tongue or pin mounted thereon.

The principal objects of the invention are 15 to provide a simple and convenient method whereby a metal, particularly a wire, member having two legs, can be permanently secured to the back of a barrette or the like made of celluloid or similar material; to 20 provide an article of that description with a tongue made of metal or wire for retaining the end of a fastening pin in accordance with said method; to provide the same article with a wire loop to which said pin can 25 be pivoted; and to provide a new and improved device for holding the end of the fastening pin.

Further objects and advantages of the invention will appear hereinafter.

Reference is to be had to the accompanying drawing in which,

Figure 1 is a rear elevation of a barrette showing the preferred form of this invention applied thereto. Fig. 2 is an end elevation of the same on enlarged scale, and 35 Fig. 3 is a sectional view on the line 3—3 of Fig. 2.

As is well understood in this art, the union of metal with celluloid is a matter of considerable difficulty. Many ways have been proposed for doing it but so far as I am aware, they are all faulty in one or more respects. One of the most common difficulties is that the metal is not firmly united to the celluloid but soon becomes loose so that 45 the value of the article is destroyed. Considerable difficulty, also, has been encountered in providing for properly retaining the end of the fastening pin with which the 50 ordinary barrette is provided. To overcome these and other difficulties, this invention is carried out as follows:—

The back of the barrette or other hair ornament 10 having as usual a plane surface

near one end to which the metal is desired 55 to be secured, is provided with a plate as 11 of nonmetallic material which can readily be cemented or otherwise firmly secured to the barrette. In the form shown, it is of celluloid and has two parallel grooves 12 60 on the back thereof. These grooves are offset at 13 in opposite diverging directions. A metallic tongue 14 or holding device for retaining the pin 20 preferably is formed of a single piece of wire bent double at the 65 end so as to form a loop and two parallel legs 15. These legs are reversely bent at 16 and their end portions are inserted in the grooves in the plate 11. At their extreme ends they are bent outwardly at 17 70 so as to fit in the off-set portion 13 of the grooves. This being accomplished, the plate 11 is cemented or secured in any other desired way, to the plane surface of the back 75 of the barrette. As the wire itself fits in the grooves, and as the bent ends fit in the off-set portions, it will be seen that the wire is firmly secured in position without cementing the wire or otherwise directly uniting 80 it with the celluloid. There is no difficulty about cementing or otherwise securing one piece of celluloid to another; consequently, the metallic member will be firmly and permanently held in position. In the present 85 case, the tongue is provided with an inward bend 27 near the top thereof and the plate 11 is provided with a projecting rib 18 directly under it. Back of the projecting rib on the celluloid piece is a groove 19. The space between the projections 27 and 18 is 90 narrower than the width of the fastening pin 20. Consequently, as that pin is forced in under the tongue, that will yield by its natural resiliency and will then spring back 95 and firmly hold the pin very securely in the groove 19. At the other end of the barrette the same principle is shown as carried out by the use of a celluloid plate 21 cemented to the rear surface of the barrette and a metallic wire loop 22 secured in position in 100 the manner above described. This loop is used as a pivot or holding and retaining device for the pin 20 in a well known way and as illustrated. It is to be observed that 105 the principle is carried out somewhat differently in detail however, as in this case the ends of the legs of the loop are in the plane of the legs and extend therefrom in oppo-

site directions while in the other case the ends 17 extend parallel to each other at right angles to the plane of the legs 16. The effect is substantially the same however.

5 The invention can be carried out in many other ways, as will be readily understood, and applied to numerous other articles and barrettes. It can be also applied to materials similar to celluloid which can be cemented or secured to like substances.

10 While I have illustrated and described a preferred embodiment of the invention I am aware that many modifications can be made 15 therein by any person skilled in the art without departing from the scope of the invention as expressed in the claims. Therefore, I do not wish to be limited to all the 20 details of construction shown and described, but

What I do claim is:—

1. As an article of manufacture, a hair ornament having a piece of non-metallic material secured to the surface thereof, said 25 piece of non-metallic material being provided with a groove in the surface thereof which is secured to the surface of the hair ornament, and a piece of metal extending along and entirely filling said groove and 30 rigidly secured to the hair ornament by the piece of non-metallic material and projecting therefrom transversely at both ends,

whereby the metal piece is secured in position.

2. As an article of manufacture, a celluloid hair ornament having a plane surface, 35 a piece of celluloid secured thereon and having a groove extending along the surface thereof which is in contact with the hair ornament, said groove having an off-set portion at one edge, and a piece of metal extending along said groove and bent at the 40 end to extend into the off-set portion and projecting from said piece of celluloid at the opposite edge thereof.

45 3. As an article of manufacture, a barrette having a celluloid plate cemented to the back thereof, and a metal tongue extending over said plate and bent reversely and extending between the plate and the 50 surface of the barrette and secured to the barrette by the plate, the outer portion of said tongue being bent inwardly near the end toward the plate and the plate having a projecting portion in registration with said 55 inward bend and a groove beyond said projecting portion for retaining a pin or tongue.

In testimony whereof I have hereunto set my hand, in the presence of two subscribing witnesses.

WILLIAM J. HINES.
